UNITED STATES PATENT OFFICE.

WALTER E. DE ARMOND, OF KNOXVILLE, TENNESSEE.

FIREPLACE.

Application filed February 20, 1922. Serial No. 538,070.

To all whom it may concern:

Be it known that I, WALTER EVARD DE ARMOND, a citizen of the United States, residing at Knoxville, in the county of Knox 5 and State of Tennessee, have invented a new and useful Improvement in Fireplaces, of which the following is a specification, reference being had to the accompanying drawing.

10 My improvement relates particularly to fire-places which are so constructed as to provide for heating by radiation of heat into the room in which the fire-place is located or to also heat water to be circulated 15 through pipes for radiation of heat at places relatively distant from the fire. That is to say, my apparatus may be so constructed as to adapt it only for radiation into the room in which the fire-place is located, or the apparatus 20 may be so constructed as to provide for such radiation and also for the circulation of water, whereby the water is heated and the heat absorbed by the water may be radiated elsewhere than at the fire-place.

25 The object of this improvement is to provide such a fire-place in which good provision is made for compelling such circulation of the combustion products as will so expose the parts of the fire-place to said combustion products as to transmit to said parts a large measure of heat, whereby the apparatus 30 is adapted to effect a maximum amount of radiation and to also communicate to water a large amount of heat.

35 Relative to the statement that water is to be heated, it is to be understood that such heating may be insufficient to convert the water into steam, or that it may be sufficient to convert the water into steam to any desired extent.

40 In the accompanying drawings,

Fig. 1 is a front elevation of a fire-place embodying my improvement, parts being broken away;

45 Fig. 2 is a plan of the same apparatus, parts being broken away;

Fig. 3 is an elevation looking toward the right of the apparatus as shown in Figs. 1 and 2;

50 Fig. 4 is an upright section on the line, 4-4, of Fig. 1, looking toward the left;

Fig. 5 is a horizontal section on the line, 5-5, of Figs. 1 and 4;

55 Fig. 6 is a horizontal section on the line, 6-6, of Fig. 4;

Fig. 7 is a perspective of one of the upright sections;

Fig. 8 is an upright section on the line, 8-8, of Figs. 10 and 11, looking toward the left;

Fig. 9 is an upright section on the line, 9-9, of Figs. 10, 11 and 12, looking toward the left;

Fig. 10 is a horizontal section on the line, 10-10, of Figs. 8 and 9;

Fig. 11 is a horizontal section on the line, 11-11, of Figs. 8 and 9;

Fig. 12 is a horizontal section on the line, 12-12, of Figs. 8 and 9;

Fig. 13 is a longitudinal section through a slip-nipple and adjoining parts;

Fig. 14 is a perspective of another form of one of the side members;

Fig. 15 is a section similar to Fig. 10, showing one of the side members in another form;

Fig. 16 is a horizontal section similar to Fig. 12, the right hand part being at a higher level and the grate being sectional;

Fig. 17 is a section similar to the upper part of Fig. 6.

Referring first to Figs. 1 to 7 inclusive, A, A are intermediate upright members, and B, B are upright side members. The side members, B, form the sides of the structure, and the space between said sides is filled with the members, A. The number of members, A, will depend upon the desired width of the structure. By increasing the number, the structure may be made wider and thus the fire-place will have larger capacity for fuel and for radiation. All the members, A, are of the same size and shape and are adapted to be fitted together with their side faces meeting.

On the forward part of the upper face of each side member, B, is an ear, B¹. A bolt, B², extends through said ears. On the upper part and on the lower part of the rear face of each side member is a similar ear, B³, and a horizontal bolt, B⁴, connects the upper of said ears and another horizontal bolt, B⁴, connects the lower of said ears. Said bolts draw the side members against the adjacent intermediate members, whereby the intermediate members are pressed against each other.

In the lower part of the space between the side members is a grate or fuel basket, C, which extends from one of said side

members to the other and rests on lugs, C¹, formed on the inner face of each side member. A binding bolt, B⁵, extends horizontally through the side members and 5 through the forward part of the base of the grate, C, whereby the side members are held against the ends of the grate.

At the upper corners and at the lower rear corner, each intermediate member and 10 each side member is provided with sockets, A⁴, the sockets on meeting faces of said members being in alignment with each other. Dowels or key members, A², extend from one of said sockets into the other, 15 whereby said upright members hold each other against movement parallel to the others of said members.

Thus the intermediate upright members, the grate, and the side members are bound 20 together to form a rigid structure. Said structure is to be set on the hearth and its rear and sides and upper part enclosed in masonry, excepting that a flue is to extend from the upper part of the structure 25 upward through the masonry, as will be described further on.

The lower ends and the upper ends, and the rear faces of the intermediate members are even with the corresponding parts of 30 the side members; but only the upper part of the front faces of the intermediate members extend forward far enough to be even with the front faces of the side members. From approximately midway between the upper and lower ends of the structure, the intermediate members recede from the front to make room for the grate or basket, C.

Each side face of each intermediate 40 member is provided with a flue recess or channel, B⁶, which extends upward from the fire-space through the upper face of said member. The two recesses on the two meeting faces of meeting members together 45 form a flue having a cross section twice as large as the cross section of one of said recesses. The upper end of each of said recesses is narrow or throat-form, while the remainder of said recess is relatively 50 wider, the forward part being bounded by the upright flange, B⁷. Opposite the lower end of said flange, a forward deflecting part, B⁸, extends obliquely forward and upward from the rear of the intermediate 55 member toward the flange, B⁷, whereby said part, B⁸, is well exposed to the heat of the products of combustion and also deflects the combustion products against the flanges, B⁷, whereby, said flanges are well 60 exposed to the heat of the products of combustion. Below the upper end of the recess, B⁶, of each intermediate member is a rearward deflecting member, B⁹, which extends obliquely downward and rearward, whereby 65 by the products of combustion are required

to move rearward and then upward, before reaching the outlet to the recess. Thus the products of combustion are retarded and sufficient contact made with all parts of the intermediate members to impart heat 70 to said members and adapt said members for radiation of heat into the space forward of the structure.

Between each side member and the adjacent intermediate member, the flue will 75 have the cross section of only one channel or recess, B⁶.

The chimney flue (not shown) meets the upper ends of the flues formed by the pairs of recesses or channels, B⁶. 80

The structure thus far described is adapted to operate without the use of water.

In the form illustrated by Figures 8 to 17, inclusive, the exterior shapes of the intermediate members and the side members and the grate are the same as in the preceding figures; but said members are hollow and connected with each other for the circulation of water to be heated and used for heat radiation from coils of pipe or other forms 90 of radiator structures.

In this second form, the key members are tubular slip nipples, A³, these nipples being substituted for the dowels, A², of the preceding form. Thus communication is formed between the several upright members and the side members. A larger detail of this connection is shown in Fig. 13. In Figs. 8, 9 and 12, parts of the grate or basket, C, are also made hollow and connected with the hollow side members by slip nipples, A³. Two such nipples are placed on the line of the binding bolt, B⁵, said bolt extending through said nipples, and the nipples being large enough to allow flow of water around the bolt. 105

At the lower end of each side member, a water inlet pipe, B¹⁰, is tapped into the outer side wall of said member. At the upper end of each side member, a water outlet pipe, B¹¹, is tapped into the outer face of said member. Circulation of water is inward through the pipes, B¹⁰, and through all the hollow parts of the side members, B, and the basket, C, and the intermediate upright members, A, and out through the outlet pipes, B¹¹. 115

The inner faces of the side members, B, may be channeled the same as are the side faces of the intermediate members, A. Such form is illustrated by Figs. 14 and 15, and the right hand part of Fig. 16. 120

When that form of side members, is used, the flue adjacent each side member is identical with the flues formed between the intermediate members.

The basket, C, may be divided transversely into sections corresponding to the intermediate sections, A. Such a form is illustrated in horizontal section in Fig. 16. The 125 130

sections of the grate are joined by slip niples, A³.

I claim as my invention,

1. In a structure of the kind described, the combination of upright side members, upright intermediate members bearing against each other and the side members and having their upper and lower and back faces and the upper parts of their front faces approximately even with the corresponding faces of the side members and being channeled on their side faces, the upper ends of the channels opening through the upper faces of said members, and means for securing said side members and said intermediate members to each other, substantially as described.

2. In a structure of the kind described, the combination of upright side members, upright intermediate members bearing against each other and the side members and having their upper and lower and back faces and the upper parts of their front faces approximately even with the corresponding faces of the side members and being channeled indirectly on their side faces, the upper ends of the channels opening through the upper faces of said members, and means for securing said side members and said intermediate members to each other, substantially as described.

3. In a structure of the kind described, the combination of upright side members, upright intermediate members bearing against each other and the side members and having their upper and lower and back faces and the upper parts of their front faces approximately even with the corresponding faces of the side members and being channeled on their side faces, the upper ends of the channels opening through the upper faces of said members, a grate, and means for securing said side members and said intermediate members and said grate to each other, substantially as described.

4. In a structure of the kind described, the combination of upright side members, upright intermediate members bearing against each other and the side members and having their upper and lower and back faces and the upper parts of their front faces approximately even with the corresponding faces of the side members and the side faces of the intermediate members and the inner side faces of the side members being channeled, the upper ends of the channels opening through the upper faces of said members, and means for securing said side members and said intermediate members to each other, substantially as described.

5. In a structure of the kind described, the combination of upright side members, upright intermediate members bearing against each other and the side members and having their upper and lower and back faces and the upper parts of their front faces ap-

proximately even with the corresponding faces of the side members and the side faces of the intermediate members and the inner side faces of the side members being channeled indirectly, the upper ends of the channels opening through the upper faces of said members, and means for securing said side members and said intermediate members to each other, substantially as described.

6. In a structure of the kind described, the combination of upright side members, upright intermediate members bearing against each other and the meeting faces of the side members and the intermediate members being channeled to form flues, a grate, means for securing said side members and said intermediate members to each other, and means extending through said side members and said grate for securing said side members to said grate, substantially as described.

7. In a structure of the kind described, the combination of upright side members, upright intermediate members bearing against each other and having their upper and lower and back faces and the upper parts of the front faces approximately even with the corresponding faces of the side members and being channeled on their side faces, the upper ends of the channels opening through the upper faces of said members, a grate, means for securing said side members and said intermediate means to each other, and securing means extending through said side members and said grate, substantially as described.

8. In a structure of the kind described, the combination of upright side members, upright intermediate members bearing against each other and the side members and having their upper and lower and back faces and the upper parts of their front faces approximately even with the corresponding faces of the side members, and the side faces of the intermediate members being channeled, the side faces of the intermediate members and the inner side faces of the side members having orifices, key members in said orifices, and means for securing said side members and said intermediate members to each other, substantially as described.

9. In a structure of the kind described, the combination of upright side members, upright intermediate members bearing against each other and the side members and having their upper and lower and back faces and the upper parts of their front faces approximately even with the corresponding faces of the side members, and the side faces of the intermediate members being channeled, the upper ends of the channels opening through the upper faces of said members, and the side faces of the intermediate members and the inner side faces of the side members having orifices, key members in

said orifices, means for securing said side members and said intermediate members to each other, a grate, and bolts binding the side members and the grate to each other, substantially as described.

10. In a structure of the kind described, the combination of upright side members, upright intermediate members bearing against each other and the side members and having their upper and lower and back faces and the upper parts of their front faces approximately even with the corresponding faces of the side members, and the side faces of the intermediate members being 10 and having their upper ends of the channels opening through the upper faces of said members, and the side faces of the intermediate members and the inner side faces of the side members having orifices, key members in said orifices, means for securing said side members and said intermediate members to each other, a grate, and bolts extending through the side members and the grate, substantially as described.

25. 11. In a structure of the kind described, the combination of upright side members, upright hollow communicating intermediate members bearing against each other and the side members and having their upper and 30 lower and back faces and the upper parts of their front faces approximately even with the corresponding faces of the side members and being channeled on their side faces, the upper ends of the channels opening through 35 the upper faces of said members, means for securing said side members and said intermediate members to each other, water induction means, and water eduction means, substantially as described.

40. 12. In a structure of the kind described, the combination of upright side members, upright hollow communicating intermediate members bearing against each other and the side members and having their upper and 45 lower and back faces and the upper parts of their front faces approximately even with the corresponding faces of the side members and being channeled indirectly on their side faces, the upper ends of the channels opening through 50 the upper faces of said members, means for securing said side members and said intermediate members to each other, water induction means, and water eduction means, substantially as described.

55. 13. In a structure of the kind described, the combination of upright side members, upright hollow communicating intermediate members bearing against each other and the side members and having their upper and 60 lower and back faces and the upper parts of their front faces approximately even with the corresponding faces of the side members and being channeled on their side faces, the upper ends of the channels opening through 65 the upper faces of said members, a grate,

means for securing said side members and said intermediate members and said grate to each other, water induction means, and water eduction means, substantially as described.

70. 14. In a structure of the kind described, the combination of upright side members, upright hollow communicating intermediate members bearing against each other and the side members and having their upper and lower and back faces and the upper parts of their front faces approximately even with the corresponding faces of the side members and the side faces of the intermediate members and the inner side faces of the side members being channeled, the upper ends of the channels opening through 75 the upper faces of said members, means for securing said side members and said intermediate members to each other, water induction means, and water eduction means, substantially as described.

80. 15. In a structure of the kind described, the combination of upright side members, upright hollow communicating intermediate members bearing against each other and the side members and having their upper and lower and back faces and the upper parts of their front faces approximately even with the corresponding faces of the side members and the side faces of the intermediate members and the inner side faces of the side members being channeled indirectly, the upper ends of the channels opening through 85 the upper faces of said members, means for securing said side members and said intermediate members to each other, water induction means, and water eduction means, substantially as described.

90. 16. In a structure of the kind described, the combination of upright side members, upright hollow communicating intermediate members bearing against each other and the side members and the intermediate members being channeled on their side faces, the upper ends of the channels opening through 95 the upper faces of said members, a grate, means for securing said side members and said intermediate members to each other, means extending through said side members and said grate for securing said side members to said grate, water induction means, and water eduction means, substantially as described.

100. 17. In a structure of the kind described, the combination of upright side members, upright hollow communicating intermediate members bearing against each other and having their upper and lower and back faces and the upper parts of their front faces approximately even with the corresponding faces of the side members and being channeled on their side faces, the upper ends of the channels opening through 105 the upper faces of said members, a grate,

- means for securing said side members and said intermediate members to each other, securing means extending through said side members and said grate, water induction 5 means, and water eduction means, substantially as described.
18. In a structure of the kind described, the combination of upright side members, upright hollow communicating intermediate 10 members bearing against each other and the side members and having their upper and lower and back faces and the upper parts of their front faces approximately even with the corresponding faces of the side 15 members, and the side faces of the intermediate members being channeled, the upper ends of the channels opening through the upper faces of said members, and the side faces of the intermediate members and the 20 inner side faces of the side members having orifices, key members in said orifices, means for securing said side members and said intermediate members to each other, water induction means, and water eduction means, 25 substantially as described.
19. In a structure of the kind described, the combination of upright hollow side members, upright hollow intermediate members bearing against and communicating 30 with each other and the side members and having their upper and lower and back faces and the upper parts of their front faces approximately even with the corresponding faces of the side members and being 35 channeled on their side faces, the upper ends of the channels opening through the upper faces of said members, means for securing said side members and said intermediate members to each other, water induction 40 means, and water eduction means, substantially as described.
20. In a structure of the kind described, the combination of upright hollow side members, upright hollow intermediate members 45 bearing against and communicating with each other and the side members and having their upper and lower and back faces and the upper parts of their front faces approximately even with the corresponding 50 faces of the side members and being channeled indirectly on their side faces, the upper ends of the channels opening through the upper faces of said members, means for securing said side members and said intermediate 55 members to each other, water induction means, and water eduction means, substantially as described.
21. In a structure of the kind described, the combination of upright hollow side 60 members, upright hollow intermediate members bearing against and communicating with each other and the side members and having their upper and lower and back faces and the upper parts of their front faces approximately even with the corresponding 65 faces of the side members and being channeled on their side faces, the upper ends of the channels opening through the upper faces of said members, a grate, means for securing said side members and said intermediate members to each other, means extending to said side members and said grate, 70 means for securing said side members to said grate, water induction means, and water eduction means, substantially as described.
22. In a structure of the kind described, the combination of upright hollow side 75 members, upright hollow intermediate members bearing against and communicating with each other and the side members and having their upper and lower and back faces and the upper parts of their front faces 80 approximately even with the corresponding faces of the side members and the side faces of the intermediate members and the inner side faces of the side members being channeled, the upper ends of the channels opening through the upper faces of said members, means for securing said side members and said intermediate members to each other, water induction means, and water eduction means, substantially as described. 85
23. In a structure of the kind described, the combination of upright hollow side members, upright hollow intermediate members bearing against and communicating 90 with each other and the side members and having their upper and lower and back faces and the upper parts of their front faces approximately even with the corresponding faces of the side members and the side faces of the intermediate members and the inner side faces of the side members being 95 channeled indirectly, the upper ends of the channels opening through the upper faces of said members, means for securing said side members and said intermediate members to each other, water induction means, and water eduction means, substantially as described. 100
24. In a structure of the kind described, the combination of upright hollow side 105 members, upright hollow intermediate members bearing against and communicating with each other and the side members and the intermediate members being channeled on their side faces, the upper ends of the channels opening through the upper faces of said members, a grate, means for securing said side members and said intermediate members to each other, means extending to said side members and said grate, 110 means for securing said side members to said grate, water induction means, and water eduction means, substantially as described. 115
25. In a structure of the kind described, the combination of upright hollow side 120 members, upright hollow intermediate members bearing against and communicating with each other and having their upper and lower and back faces and the upper parts of their front faces approximately 125

even with the corresponding faces of the side members and being channeled on their side faces, the upper ends of the channels opening through the upper faces of said members, a grate, means for securing said side members and said intermediate means to each other, securing means extending through said side members and said grate, water induction means, and water eduction means, substantially as described.

26. In a structure of the kind described, the combination of upright hollow side members, upright hollow intermediate members bearing against and communicating with each other and the side members and having their upper and lower and back faces and the upper parts of their front faces approximately even with the corresponding faces of the side members, and the side faces of the intermediate members being channeled, the upper ends of the channels opening through the upper faces of said members, and the side faces of the intermediate members and the inner side faces of the side members having orifices, key members in said orifices, means for securing said side members and said intermediate members to each other, water induction means, and water eduction means, substantially as described.

27. In a structure of the kind described, the combination of upright hollow side members, upright intermediate members bearing against each other and the side members and having their upper and lower and back faces and the upper parts of their front faces approximately even with the corresponding faces of the side members and being channeled on their side faces, the upper ends of the channels opening through the upper faces of said members, a hollow grate communicating with the side members, means for securing said side members and said intermediate members and said grate to each other, water induction means, and water eduction means, substantially as described.

28. In a structure of the kind described, the combination of upright hollow side members, upright intermediate members bearing against each other and having their upper and lower and back faces and the upper parts of the front faces approximately even with the corresponding faces of the side members and being channeled on their side faces, the upper ends of the channels opening through the upper faces of said members, a hollow grate communicating with the side members, means for securing said side members and said intermediate means to each other, and securing means extending through said side members and said grate, substantially as described.

29. In a structure of the kind described, the combination of upright hollow side members

having approximately parallel front and rear faces and being of a width equalling the measurement of the structure from front to rear, upright intermediate members bearing flatwise against each other and the side members and the dimension of their upper parts from front to rear equalling the like dimension of the side members whereby the rear faces of said intermediate members are even with the rear faces of the side members and the upper parts of the front faces of the intermediate members are even with the front faces of the side members and the meeting faces of the intermediate members having flue channels, and means for securing said side members and said intermediate members to each other, substantially as described.

30. In a structure of the kind described, the combination of upright side members having upright front faces adapted to be placed even with the outer face of a wall, upright intermediate members bearing against each other and the side members and having the upper part of their front faces approximately even with the front faces of the side members, the meeting faces of said members having orifices, key members in said orifices, the side faces of the intermediate members having flue channels, and means for securing said side members and said intermediate members to each other, substantially as described.

31. In a structure of the kind described, the combination of upright side members having upright front faces adapted to be placed even with the outer face of a wall, upright hollow communicating intermediate members bearing against each other and the side members and having the upper part of their front faces approximately even with the front faces of the side members, the side faces of the intermediate members having flue channels, induction means, education means, and means for securing said side members and said intermediate members to each other, substantially as described.

32. In a structure of the kind described, the combination of upright side members having upright front faces adapted to be placed even with the outer face of a wall, upright hollow intermediate members bearing against each other and the side members and having the upper part of their front faces approximately even with the front faces of the side members, the meeting faces of said members having orifices, key members in said orifices, the side faces of the intermediate members having flue channels, and means for securing said side members and said intermediate members to each other, substantially as described.

33. In a structure of the kind described, the combination of upright hollow side members having approximately parallel

front and rear faces and being of a width equaling the measurement of the structure from front to rear, upright hollow communicating intermediate members bearing 5 flatwise against each other and the side members and the dimension of their upper parts from front to rear equaling the like dimension of the side members, whereby the rear faces of said intermediate members are even 10 with the rear faces of the side members and the upper parts of the front faces of the intermediate members are even with the front faces of the side members and the meeting faces of the intermediate members having 15 flue channels, induction means, eduction means, and means for securing said side members and said intermediate members to each other, substantially as described.

34. In a structure of the kind described,

the combination of upright side members 20 having approximately parallel front and rear faces, upright intermediate members bearing against each other and the side members and having the upper part of their front faces approximately even with the 25 front faces of the side members, the side faces of the intermediate members having flue channels and the meeting faces of said members having orifices, key members in said orifices, and means for securing said 30 side members and said intermediate members to each other, substantially as described.

In testimony whereof I have signed my name, this fifteenth day of February, in the year one thousand nine hundred and twenty- 35 two.

WALTER E. DE ARMOND.
